UNITED STATES PATENT OFFICE

2,508,483

METHOD FOR CONTROLLING THE CONTOURS OF RAYON CAKES

Willem Bakker, Arnhem, Netherlands, assignor to American Enka Corporation, Enka, N. C., a corporation of Delaware

Application November 28, 1947, Serial No. 788,701
In the Netherlands June 16, 1947

1 Claim. (Cl. 18—54)

1

This invention relates to the pot spinning of rayon yarn and is more particularly related to the control of the contours of the wound cake between the termination of the spinning period and the commencement of the first aftertreating operation.

When viscose rayon is spun according to the pot spinning process, the completed cake is ordinarily removed from the pot by turning the pot upside down and discharging the cake onto a flat plate. The axial section of such a cake conforms to the axial section of the frustum of a hollow cone, the top and bottom as well as the inner and outer surfaces being straight. The cake, in this condition, is ordinarily stored for a period of time in order to permit the regeneration of the cellulose to proceed to conclusion, and then the cake is placed between two plates which are parallel to each other and normal to the long axis of the cake in order to subject it to after-treatment such as the removal of acid by washing, or color improvement by bleaching.

Because of the construction of conventional apparatus for the effecting of the aftertreatment, it is absolutely essential that the spacing between the plates which hold the cake during after-treatment be maintained at a fixed value. It has been found, however, that during the storage period immediately following the spinning period, cakes have a tendency to grow upwardly along the upper edge of the inner surface so that the upper surface of the cake, after storage, is no longer a flat annulus but rather, slopes upwardly toward the center. When a cake deformed in this manner is placed between the two plates for aftertreatment, it is apparent that the raised portion must be again depressed if the plates are to assume the desired spaced relation relative to one another which is required by the machine. As a matter of fact, it has been found that pressures reaching several tens of kilograms per cake must be applied in order that the plates at the top and bottom of the cake can be moved together to their normal operating position. The exertion of pressures of this order has a tendency to compress the raised portion of the cake and to form an annulus projecting into the hollow interior of the cake near the top edge thereof. During the compression of the cake and the formation of its annulus, thread layers are required to slide over one another which may cause damage, and the resulting shape of the cake, that is, the presence of the inwardly protruding annulus near the top of the cake, causes the cake to wash un-

2

evenly and results in bad unwinding and excessive waste.

While the foregoing phenomenon is present to some extent in all cakes, it has been found that it is particularly pronounced where the thread has been in contact with water or aqueous solutions after it has left the spinning bath and before it enters the spinning pot. This situation occurs in two-bath spinning where the thread is stretched in a second dilute aqueous bath between the spinning and the collection. Furthermore, it is found that in cases of high denier yarns such as are used in the production of tire yarns, the growth phenomenon is serious.

15 It is therefore an object of this invention to overcome the foregoing difficulties and to provide for the storage of freshly spun cakes in such a way as to prevent distortion of the cake contour with its concomitant disadvantages.

20 It is contemplated according to the present invention to locate the freshly spun cake between two spaced plates located a distance apart equal to the height of the freshly spun cake and the distance between the plates which hold the cake during the aftertreating operation.

25 It is a further object of this invention to control the contour of the freshly spun cake during the aging period preceding the aftertreating operations in such manner that the plant operators are protected from the evolution of dangerous gases such as carbon disulphide during the aging period.

30 Other objects and advantages of this invention will be apparent upon consideration of the following detailed description thereof in conjunction with the annexed drawings wherein:

35 Figure 1 is a vertical sectional view of a freshly spun cake of rayon yarn placed in storage for aging in accordance with the principles of the present invention;

40 Figure 2 is a top plan view of the subject matter of Figure 1; and

45 Figure 3 is a perspective view of the details of a latching mechanism constituting a part of the present invention.

50 Referring now to the drawings in greater detail, the arrangement shown consists of a bottom plate assembly 10 including a collar 11 which has extending from the base thereof an annular flange 12. Near the center of the bottom plate assembly 10 there is provided a frusto conical boss 13 which extends considerably above the upper edge of the collar 11. It can be seen, however, that a flat annular space is provided between the boss 13 and the collar 11, and it is this space on which the

cake 14 rests during the storage period after spinning.

The bottom plate assembly 10 is arranged to cooperate with a lid 15 which is provided with a rolled bottom edge 16 that engages the plate assembly as it is forced down over the collar 13 and comes to rest on the flange 12. Note also that the collar 11 is internally tapered and has an internal cross section of such shape that the top edge of a standard spinning pot will fit into it. Thus, the inverted bottom assembly fits in centralized position around the edge of a spinning pot.

It should also be noted that the bottom plate assembly has been so constructed that a number of these can be piled one upon another so that they occupy as little space as possible.

The remainder of the apparatus disclosed in Figures 1 and 2 can probably be best understood by reference to the use thereof in actual practice. At the doff, the bottom plate assembly is placed upside down on the spinning pot as soon as the spinning pot lid has been removed. The bottom plate assembly fits in a centralized position on the spinning pot. The pot and plate assembly are then inverted so that the cake 14 rests in the position shown in Figure 1. The pot is then removed and the lid 15 is placed in the position shown in Figure 1 overlying the cake 14. The height of the lid has been so chosen that, in its coacting position with the bottom plate assembly, the vertical distance between the upper surface of the annular space between the boss and the collar on the bottom plate assembly and the corresponding surface of the lid 15 is equal to the height of the cake, with perhaps one or two mms. to spare to compensate for minor variations in the height of the spun cake.

The lid 15 is attached to the bottom assembly 10 by means of two flat steel plates 17 and 18 which can best be seen in Figure 3. The two steel plates are pivotally mounted at 19 and 20 respectively and are spring urged such that the steel plate 17 is biased in a counterclockwise direction as viewed in Figure 2, while the steel plate 18 is biased in a clockwise direction, as it is in that figure. The steel plates cooperate with a bolt 21 which is held by a nut 22 at the top of the boss 13 in the bottom assembly 10. The bolt 21 is cylindrical throughout most of its length but is provided with an annular groove at 22 adapted for the reception of edge portions of the steel plates 17 and 18. When the lid 15 is placed in operative position, the steel plates 17 and 18 are moved apart during passage over the rounded-off top portion of the bolt 21; and, when they register with the plane of the groove at 22, they fall into it and so lock the bolt to the lid assembly. In order to release the plates 17 and 18, a key-hole at 23 is provided in which a key, not shown, may be mounted for rotation to bear against vertical flanges 17a and 17b of the members 17 and 18 to move them apart and out of the slot 22 to permit removal of the lid 15.

During the aging period between the insertion of the cake into the apparatus shown in Figures 1 and 2 and the removal thereof from that apparatus preparatory to soaking for the first of the aftertreating operations, it is apparent that the height of the cake cannot grow more than a very few mms. After the aging period there is no tendency for the height of the cake to change

any more so that all cakes which are stored in the apparatus of the present invention have flat top and bottom surfaces lying equal distances apart, and these are readily received in between the plates which hold them for the aftertreating operation. It might be supposed that since cakes during the aging period have a tendency to grow upwardly, that they would exert a very large force on the bottom plate and lid constituting the assembly of Figures 1 and 2. It has been found however that although a freely grown cake requires very considerable force to flatten it, the restraining force necessary to maintain the cake in the desired shape is relatively slight.

It is apparent from the foregoing, as far as cake growth is concerned, the results could be achieved by any arrangement involving two spaced plates bearing on the bottom and top surfaces of the cake and held in a fixed relative position. An additional advantage of the present construction is, however, that the gases which evolve during the aging of the cake, such as carbon disulphide, are retained within the housing defined by the bottom plate assembly 10 and the lid 15 so that the storage room, or whatever space is used for storing the cakes during the aging period, is kept free of the dangerous and toxic gases evolved. When the cakes are removed for washing this can be done in an area of good ventilation and even the boxes themselves can be provided with vents so that they can be evacuated before they are opened.

It is perfectly apparent that transportation of these boxed cakes is much more easily effected than transportation of the cakes in unboxed form since danger of injury to the yarn cake is greatly reduced.

While the foregoing invention has been described with reference to but a single embodiment thereof, it is to be understood that various modifications are contemplated as lying within the scope of the appended claim.

What is claimed is:

The method of inhibiting the axial growth of freshly spun cakes of rayon yarn that comprises removing the cover from the spinning pot at the termination of the spinning period, substituting a plate presenting a flat cake end-supporting surface, inverting the pot with the plate in position, removing the pot while leaving the cake on the plate, locating another member having a flat yarn end-contacting surface over the upper end of the cake, drawing said member toward said plate until the member almost touches the upper end surface of the cake establishing a gas proof zone around the cake and storing the cake between the member and the plate for the time period after the formation of the cake and prior to the first aftertreating operation.
